MACHINE FOR USE IN THE MANUFACTURE
OF SHOESRobert H. Lawson, Beverly, Mass., assignor to
United Shoe Machinery Corporation, Flemington,
N. J., a corporation of New Jersey

Application June 28, 1944, Serial No. 542,546

23 Claims. (Cl. 12—4)

1

The present invention relates to machines for use in the manufacture of shoes, and more particularly to machines which comprise in their organization devices for performing an operation progressively along the bottom margin of a shoe, a shoe supporting jack and mechanism for controlling the relative positions of the jack and operating devices as the point of operation of said devices is transferred along the shoe, the invention being herein disclosed as embodied in and intended as an improvement of automatic side lasting machines such as disclosed in various United States Letters Patent, including United States Letters Patent No. 2,252,325, granted August 12, 1941; No. 2,247,443, granted July 1, 1941; and No. 2,201,866, granted May 21, 1940, all upon applications filed in the name of the present inventor.

The jack disclosed in inventor's Patent No. 2,201,866 has a frame connected by a substantially horizontal link with a vertical arm pivotally connected with a movable jack base comprising a follower arm actuated by a pattern cam for imparting longitudinal pitching or tipping movements to the shoe on the jack about an axis passing through the plane of the shoe bottom at the point of operation transversely to the length of the shoe. The machine is provided with lasting units having presser feet engaging the bottom of the shoe at each side of the shoe and, in order to insure equal pressures on the presser feet, the means for supporting the shoe is carried in a cradle pivotally mounted in the frame of the jack about an axis extending lengthwise of the shoe, thus permitting rolling or rocking movement of the shoe about the lengthwise axis. The arrangement of the jack and the operating means therefor in the patented machine is effective for the purposes intended when a man's shoe having a relatively flat bottom surface is being lasted but, with a woman's style high-arch shoe, so much pitching movement is required in the jack frame in order to present the shoe bottom properly to the lasting units that a cam for producing these movements will have a curvature of an excessively steep inclination, and the parts of the jack including the arm and the frame will be inclined to such a degree with relation to each other that the desired pressures will not be maintained

2

on the presser feet, and other difficulties may arise due to mechanical disarrangement of the parts.

In the machine embodying the present invention, little or no relative angular movements are required between the jack frame and its supporting arm while lasting women's style shoes, or at least no greater movements than with men's style shoes having relatively flat bottom surfaces, the shoe supporting means not being carried directly in the cradle but in a separate carriage which, in turn, is mounted in the cradle for relative pitching movement of the shoe about an axis extending widthwise of the shoe. Suitable movements are imparted to the carriage relatively to the cradle during operation on the shoe while the lasting units are operating along the ball portion of the shoe, so that the angular relation of the jack frame and its supporting arm may be maintained without substantial change, or at least with no more change, while operating upon a woman's style shoe having a high arch than upon a man's shoe having a relatively flat bottom surface. In this feature of the invention, the mechanism for shifting the carriage is driven from a cam shaft mounted in the jack frame.

As has been stated, the principal movement of the carriage in the jack cradle occurs while operating upon the ball portion of a woman's style shoe between the shank and forepart. Along other portions of the shoe, pitching movements are necessary only to the extent corresponding to those required in a man's style shoe, so that such movements may be taken care of readily by a pitch cam of a shape formerly employed in the patented machine. To insure that no relative movements between the carriage and the cradle will occur at times other than while the ball portion of a woman's shoe is being operated upon, the mechanism for shifting the carriage in the cradle includes disconnectible connections driven from the cam shaft and means for connecting said connections while the ball portion of a shoe is being operated upon and for disconnecting and locking the connections thereafter. In one form of this feature, the means for causing the disconnectible connections to be connected and disconnected includes a crank driven by the cam shaft.

The shoe supporting means of the patented machine consists of a last pin and a toe rest, the last pin being mounted upon a slide movable toward

and from the toe rest and urged yieldingly toward the toe rest to clamp a shoe on the supporting means. In order to maintain the supporting means in readiness to receive a shoe, the last pin slide is, as usual, releasably held away from the toe rest, and in the patented machine the last pin has slidably mounted on it a depressible plunger actuated while a shoe is being applied to the jack to release the jack pin slide for clamping movement toward the toe rest. Actuation of the plunger while applying a shoe to a jack of the type referred to may require excessive effort on the part of the operator or the actuating mechanism may be strained excessively on account of the force frequently applied to the shoe in actuating the slide releasing plunger.

Accordingly, a further feature of the present invention resides in a tripping lever for the shoe clamping means mounted directly in the jack frame and having a handle portion located in line with the axis about which the cradle pivots in the frame. With this arrangement, the operator in applying the shoe to the jack may grasp the shoe conveniently and actuate the tripping lever without exerting excessive effort and, at the same time, the shoe may easily be guided during its movement with the last pin toward the toe rest, the parts of the jack taking naturally their proper positions while presenting the shoe to the lasting units.

In the machine of the present inventor's earlier Patent No. 2,201,866, mechanism is provided for exerting an upward raising pressure on the jack during operation on a shoe and for lowering the jack at the end of the operation, which comprises a spring and a toggle, the spring being rendered inoperative and locked out of operation by straightening the toggle. The movement of the toggle to straightened position lowers the jack and is accomplished through connections including a pattern cam actuated lever. Due to the nature and general arrangement of the machine, the jack lowering movement must be imparted rapidly during a relatively small number of degrees of rotation of the pattern cam. On account of the weight of the jack and the connected parts, rapid movement of the toggle to straightened position causes an objectionable degree of shock and jar from reaction produced by stopping the lowering movement of the jack. To overcome this difficulty in the machine of said Patent No. 2,247,443, the toggle has a dashpot connected to it arranged to resist movement of the toggle as it approaches straightened position, thereby delaying the lowering time of the jack and absorbing shock and jar at the end of a lasting operation.

An important object attained in the construction embodying the present invention, therefore, is to avoid the necessity of employing a dashpot connected to the toggle as in the machine of Patent No. 2,247,443 and, generally, to improve the operation of the jack and its actuating mechanism of that machine. A feature of the invention, accordingly, consists in the use of novel and improved means, separate from the jack raising spring employed in the patented machine, for counterbalancing the weight of the jack substantially to avoid shock and jar in the toggle and its actuating mechanism of the machine.

Another feature of the invention, contributing to the attainment of the above objects relates to a loose joint in the connections through which the jack raising spring acts, the counterbalancing means enabling the jack to move relatively to the

toggle slowly for a short distance after the toggle is straightened without subjecting the toggle to undesirable shock or jar.

These and other features of the present invention, including novel cam means on the operating shaft for increasing and diminishing the pressure of the shoe on the operating devices, will be readily understood by those skilled in the art from the following specific description taken in connection with the accompanying drawings in which is illustrated so much of an automatic side lasting machine as is necessary to show the improvements and connections of the present invention therewith.

Referring to the drawings,

Fig. 1 is a view in side elevation, looking from the left, of a machine embodying the present invention, with the side of the frame broken away and in section to show the underlying parts;

Fig. 2 is a view in front elevation, on an enlarged scale, of the shoe supporting jack and the disconnectible connections of its actuating mechanisms, with the parts unlocked and in connected positions, assumed just after the start of the lasting operations:

Fig. 3 is a detail view of the disconnectible carriage actuating connections while the parts are in the positions assumed at the end of a lasting operation with the connections locked;

Fig. 4 is a perspective view on an enlarged scale of the carriage actuating connections in locked positions at the beginning of a lasting operation;

Fig. 5 is a view in elevation, partly broken away, of the jack frame and the carriage actuating connections with the parts in locked positions at the beginning of an operation;

Fig. 6 is a view in side elevation, looking from the right, of the upper portion of the jack illustrated in Fig. 5;

Fig. 7 is a detail sectional view, on an enlarged scale, of the cam shaft for actuating the carriage mechanism, taken along the line VII-VII of Fig. 5;

Fig. 8 is a perspective view of a portion of the cam shaft;

Fig. 9 is a plan view, on an enlarged scale, of a portion of the carriage actuating connections and the controller therefor;

Fig. 10 is a view in side elevation of the same parts;

Fig. 11 is a detail plan view of the hooked disconnectible element of the connections; and

Fig. 12 is a perspective view of certain of the jack raising connections.

The automatic side lasting machine illustrated in the drawings is the same, except as herein-after described, as the machine disclosed in inventor's prior patents hereinbefore referred to.

Referring more particularly to Fig. 1 of the drawings, the lasting units of the machine are provided with upper gripping, tensioning and staple driving devices and are generally indicated at 2, the operating cam shaft at 4, and the pattern cams at 6, 7 and 8 on two shafts 10 and

12 arranged horizontally and at right angles to each other and rotated in unison with a step-by-step or intermittent motion, once during each operation on a shoe, through connections with the operating shaft 4. The shoe supporting jack comprises a frame 14 having shoe supporting means therein and a supporting structure including a horizontal link 16 pivotally connected to the frame and to an upwardly extending substantially vertical arm 18 which, in turn, is supported by a base 20 pivotally mounted upon the frame-

work 22 of the machine to swing about an axis extending transversely to the direction of feed and substantially parallel with the plane of the bottom of a shoe supported on the jack. The pivots connecting the link 16 with the arm 18 and with the jack frame 14 are parallel with the axis of the base 20. The jack frame is thus supported firmly in position but can readily be moved to feed the shoe and to impart a pitching or tipping movement to the shoe about an axis extending through the shoe bottom transversely to the length of the shoe at all times during the operation of the machine. To permit a slight lateral movement of the jack frame during the lasting operation and also a movement of the jack frame into and out of operative position with relation to the lasting units, the supporting arm 18 is pivotally mounted at its lower end on the base 20 to swing about a horizontal axis at right angles to the pivotal axis of the base in the main machine framework. Feeding movements are imparted progressively and intermittently to the jack frame 14 through connections actuated by the pattern cam 1, including a cam actuated lever 24, a link 26 having its lower end adjustably connected to the lever 24 in a manner clearly described in Patent No. 2,201,866 and having its upper end connected to a horizontal arm of a bell crank 28 and a link 30 connecting the vertical arm of the bell crank to the jack frame.

During operation of the machine, the jack is continually raised and forced upwardly by means of a relatively long tension spring 32 connected at its lower end to one arm of a lifting lever 34, acting through a jack supporting cord 36 running over suitably located guides and pulleys to the frame of the jack. During work feed, the pressure of the shoe against the lasting units and the tension of the jack raising spring are increased and alternately diminished and, at the end of the feeding movement are again increased to insure proper staple driving operations in a manner to be described further hereinafter. Prior to the outward movement of the jack at the end of a lasting operation, the force of the spring on the jack frame is relieved and the jack lowered away from the lasting units, as in the machine of the said patents, this result being accomplished during the straightening movement of a toggle comprising links 38 and 40, the latter of which comprises a pair of similar bars, one at each side of the link 38. The lifting lever 34 is fulcrumed on a shaft 35 in the machine framework 22 and the upper link 38 of the toggle is pivoted to the machine framework. The lower link 40 of the toggle is pivoted to a toggle supporting arm 42 carrying a set screw 44 (see Fig. 12) engaging a lug on a second arm of the lever 34. The toggle is flexed more or less during the operation on the shoe as the spring takes up or gives up the chord 36 to which it is connected, the parts of the jack supporting structure being foreshortened vertically as the position of the shoe is changed.

To straighten the toggle and lower the jack at the end of a lasting operation, the toggle link 40 is connected by a link 46 to a cam actuated lever 48. As the toggle approaches its straightened condition, a link 50 connected to the toggle link 38 forces a slide 52 to which it is pivoted outwardly through a bearing in the machine base and causes the outer end of the slide to engage a plate 54 on the jack frame 14, thereby forcing the jack outwardly away from its operating position. While in its outer inoperative position, the

jack is actuated automatically to release the shoe, and a new shoe is substituted manually for one which has been lasted.

To present the shoe properly to the lasting units during lasting operations, it is desirable to tip the shoe with an endwise pitching movement and with a widthwise rocking or rolling movement. The rolling movement is provided for in the patented machine by securing the shoe supporting means in a cradle, similar to that indicated at 56, having pivotal mountings 58 on the frame 14, the axis of which mountings passes through the shoe bottom lengthwise of the shoe. During lasting operations, the cradle is shifted in the jack frame to insure proper positioning movements of the shoe. The construction and operation of the cradle in its pivotal mountings in the present machine are similar to those in the patented machine.

The tipping or pitching movement of the shoe in the patented machine is centered about an axis passing through the bottom of the shoe at the point of operation of the lasting units 2 determined by abutments comprising a pair of presser feet 60 acting at opposite marginal portions of the shoe and engaging the insole of the shoe indicated at 62 on a last 63 inside the ribs of the insole.

With shoes having relatively flat bottom surfaces, such as are encountered in the ordinary run of men's styles, the construction and design of the jack actuating mechanism and cams in the patented machine are adequate to produce the desired positioning movements. With high-arch shoes styled for women's wear, relatively abrupt curvatures are met, particularly along the ball portion of the shoe, so that the extent and rapidity of movements required in tipping the shoe may impart excessive strain on the jack actuating mechanism. Also, the cams required for producing the resulting pitching movement necessarily have their active surfaces formed with excessively hard inclinations where tipping or pitching movements are rapid or excessive. In some instances, the vertical foreshortening of the jack parts as the result of tipping or pitching the shoe is so great as to reduce below a desirable minimum the pressure exerted by spring 32 on the jack so that the shoe may not be held effectively in operating position against the presser feet 60.

In order to avoid these difficulties and to impart the proper tipping or pitching movement to a woman's style shoe having a relatively high arch, according to the present invention, the shoe supporting means is not mounted directly in the cradle 56 but upon a separate carriage 64 which in turn is mounted in the cradle 56 for arcuate tipping or pitching movement, thus avoiding the necessity of tipping the jack frame while operating upon high-arch shoes to the full extent required by the curvature of a shoe bottom. With the use of a separate carriage, substantially the same shape may be employed in the pattern cam 8 for producing the pitching movement of the jack frame with women's shoes as is used with men's shoes by introducing the excess of pitching movement required in women's shoes through tipping of the carriage only. With men's shoes, the carriage may be locked in position in the jack frame throughout the operation so as to be held immovable with relation to the cradle.

The carriage 64 is formed with two pairs of oppositely disposed slots 66 of arcuate shape having a curvature centered about an axis, indicated

at 68, passing through the ball portion of a shoe on the carriage, a short distance beneath the bottom surface of the shoe. Fitting within the slots are two pairs of aligned rolls 67 (see Fig. 5) rotating on stub shafts 69 projecting toward each other from the cradle 56. With different sizes of shoes, necessarily there will be some variation in the location of the pitching axis, but the arrangement is such that the axis 68 passes through shoes of various sizes at locations generally concentric with the curvature of the ball portion of the shoe. When located in this manner, a substantially uniform pitching movement in the carriage is suitable for proper presentation of the shoe to the lasting units, and all sizes of shoes with a particular style have been found to effectively be operated upon.

The mechanism for actuating the carriage in the cradle is driven from a cam shaft 70 in the jack frame 14, the cam shaft being in turn rotated somewhat less than 90° during the lasting operation and then reversed to starting position through suitably connected cords 72, arranged and actuated as more fully described in inventor's Patent No. 2,201,866. Since the extent for pitching movements required is greater at the ball portion of a shoe than during operation along the forepart where little or no pitching movement is required, the actuating connections between the cam shaft and the carriage 64 are arranged to be locked and disconnected during lasting operations along the forepart of a shoe and to be unlocked and connected together for operation only along the ball portion and shank of the shoe. An important advantage gained by disconnecting and locking the carriage pitching mechanism results not only from securing the carriage firmly in position while operating upon the relatively flat forepart of a shoe but also by avoiding the necessity of imparting a reverse movement to the carriage while the cam shaft 70 is being reversed at the end of a lasting operation. The shaft 70 also carries a cam 71 (Figs. 1 and 7) which acts upon a lever 73 to cause the cradle 56 to be shifted in the jack frame, as in the patented machine.

The disconnectible connections between the shoe pitching or tipping carriage and the cam shaft 70 in the jack frame include a link 74 connected at its upper end by a universal joint to the carriage 64 near the toe of the shoe supported thereon and by a similar joint at its lower end to the longer arm of a double lever 76, forming a carriage actuator fulcrumed on a pin 78 mounted at its ends in the side flanges of the jack frame 14. The arms of lever 76 are disposed substantially at right angles to each other, the shorter one being pivotally connected at 79 to a link 80 acting, together with a link 82, as a toggle for locking the actuator lever 76 while operating upon the forepart of the shoe. The actuator lever is constructed with two similar parts spaced from each other with a hub of the link 80 between them at the end of the shorter arm. To prevent the locking toggle from moving past straightened position, the link 80 has a downwardly extending lug for engaging the inner surface of the link 82 when the pivots of the toggle are brought into alignment. The link 82 of the toggle has a hub rotatable on a pin 84 in the jack frame, the parts being so arranged that, when the toggle is straightened, the carriage 64 is held immovable in the cradle 56 (Figs. 3 and 5). When the locking toggle is broken, the actuator lever 76 is connected with one arm of a cam lever 86 fulcrumed on the pin 84 and pro-

vided on its other arm with a cam roll 85 (Fig. 4) engaging a suitably shaped cam slot cut in a cam plate 88 (see Fig. 7) secured to a disk 90 keyed to a sleeve 92 on the cam shaft 70, the shape of the cam slot being indicated by the dot-dash line of Figs. 2 and 5. The cam plate 88 is shaped with a bulge to impart suitable movements to the carriage actuator lever 76 for preventing the shoe properly to the lasting units during operation along the ball portion of the shoe in the jack. During the remainder of each operation upon a shoe, the cam roll on the lever 86 is engaged by a portion of the cam slot in the plate 88 which is concentric with the cam shaft, so that no movement is imparted to the cam lever.

The disconnectible element of the carriage actuating connections consists of a hooked link 94 mounted on the pivot 79 between the parts of the actuator lever 76 and arranged with its hooked end to engage a pin 96 fixed in one arm of the cam lever 86 as best shown in Figs. 10, 11 and 12.

In actual practice, it has been found that the curvature along the ball portion of a woman's shoe throughout the normal range of shoe sizes of a particular style is substantially the same. For this reason, the shape of the slot in cam plate 88 is suitable for imparting pitching movement to all sizes in at least one style of shoe and in many other styles of similar nature.

When the hooked link 94 is disengaged from the pin 96, the locking toggle 80, 82 is held in straightened condition by a spring 98 coiled about the hub of the toggle link 80 on the pin 79, one end of the spring acting against a projection carried by the toggle link 80 and the other end against the hub of a controller 100, more fully described hereinafter, rotatably mounted on the pin 78. The hooked link is arranged to be held either in engagement with or disengaged from the pin 96 by frictional force exerted by a flat spring 102 surrounding at one end a hub of the hooked link 94 and formed with a grooved free end to engage frictionally with the end surface of the pin 96 while the link 94 is hooked thereto. To insure that the flat spring 102 will move with the hooked link, it is riveted along its middle portion to the link. The spring 102 is constructed to exert a pressure at its free end against the hooked portion of the link 94 and is disposed to press frictionally against the end surface of the pin 96, thus holding the hooked link in engagement with the pin.

The controller 100 for the hooked link 94 consists of a lever formed with crossheads at its ends rotatably mounted on the pivot pin 78 for the actuator lever 76. The crossheads of the controller lever are disposed to engage the outwardly projecting tail of the hooked link 94 in one position of the controller and the hooked portion of the link in the other extreme position of the controller. The left-hand crosshead on the controller is provided with an elongated slot within which projects a stud 104 carried by a controller shifting arm 106 rotatable about the pin 78. The shifting arm 106 is actuated by a crank rotating with the cam shaft 70 which is so timed that, when the toggle 80, 82 is moved to aligned position to lock the carriage actuator lever 76, the arm 106 will shift the controller against the tail of the hooked link 94 and disengage it from the pin 96. The controller lever 100 is retained yieldingly in uniform angular relation with the arm 106 through a spring 108 connecting the controller with the arm, thereby

holding the controller with the upper end of the slot against the stud 104. When the arm 106 is moved in the opposite direction, the controller presses against the hooked portion of the link 94 and engages it with the pin 96 if the pin is in a position to be received by the hooked portion of the link 94. If the pin 96 is out of alignment with the hooked portion of the link 94, the pin may engage an extension of the link and ride along the under surface of the link until proper alignment is reached. During this time, the angular relation of the controller and arm 106 will be changed, the spring 108 expanding sufficiently to enable the slotted crosshead of the controller to be moved yieldingly through the length of the slot. As soon as the pin comes into alignment with the hooked portion of the link 94, the spring 108 will press the hooked link into connecting position. The crank on the cam shaft 70 for actuating the controller shifting arm 106 comprises a bolt 110 threaded into one side of the disk 90, passing loosely through a pitman 112 having its crank engaging end curved about the cam shaft and its outer end pivotally connected at 114 to the arm 106.

To break alignment of the toggle links 80, 82 before the lever 86 begins to move, the disk 90 has bolted to one side a radially projecting arm 116, best shown in Fig. 8, upon which is pivotally mounted a latch 118. The latch 118 is located to engage an inwardly extending finger portion of the link 82 at a time just before the roll on the cam lever 86 enters an active portion of its cam slot. Continued rotation of the cam shaft and disk 90, after the latch 118 engages the link 82, moves the toggle toward broken position and unlocks the actuator lever 76. The latch 118 is arranged to yield upon engagement with the link 82 during reverse rotation of the cam shaft, a tension spring 120 being connected between a tail on the latch and an anchor pin on the disk 90. To maintain the latch in idle position when disengaged from the link 82, a stop pin 121 is mounted in the arm 116 to limit the movement of the latch by the spring 120. After the cam roll has passed through the active portion of the cam slot in the plate 88, the actuator lever 76 is returned to its starting position, and the toggle 80, 82 is brought into locking alignment, being held in this position by the spring 98.

During the return rotation of the cam shaft 70 from the position of Fig. 3 to its starting position of Fig. 5, in readiness for a new operation, the toggle 80, 82 remains straightened, thus locking the carriage actuating connections, and the hooked link 94 remains disengaged from the pin 96 with the actuating connections thus disconnected. An important advantage of this mode of operation results in saving time and reducing the strain on the operating connections in moving the relatively heavy shoe carriage and shoe supporting parts. With the connections disengaged, no resistance is offered by the weight of the parts actuated, so that a relatively rapid return movement can be accomplished. Rotation of the cam shaft 70 is utilized also to release the shoe from the jack and reset the jack in readiness for the reception of a new shoe.

For supporting and clamping the shoe in the carriage 64, the carriage has a toe rest and a heel support or post. The toe rest is mounted at the right end of the carriage and comprises a curved chute 122. The heel support comprises a last pin 124 slidably mounted for movement on the carriage toward and from the chute. The last pin

124 is mounted on a post 125 projecting from a slide 126 movable along a guideway 128 in the carriage, a shoe clamping spring 130 being stretched between the slide and the right end of the guideway to force a shoe in which the last pin is inserted toward the toe rest chute. To simplify the construction, the chute 122 is not pivotally mounted on the toe end of the jack as is the chute in inventor's Patent No. 2,252,325 but is fixedly secured by an angle bracket 132 to the toe rest end of the shoe carriage. The guideway 128 in the carriage is inclined at an angle to the length of the last pin 124 so that, with small sizes of shoes, the last pin as it moves toward the toe rest will rise progressively to a higher level with respect thereto in compensation of the lower heights of last.

To prevent displacement of the shoe and to locate the extreme end of a shoe on the jack as the last pin clamps the shoe against the toe rest, the toe rest is provided with a toe end gage 134 in the form of a plate screwed to the toe rest portion of the carriage and bent at its upper end with its toe end engaging surface substantially at right angles to the length of the last pin guideway 128. By this arrangement, the upward component of force imparted to the shoe by the last pin spring 130 acting in the direction of the guideway 128 is resisted at the toe of the shoe and there is no tendency to force the shoe upwardly away from the toe rest chute 122.

The connections between the cam shaft 70 and the last pin supporting slide 126 for unclamping and releasing the shoe are similar to those disclosed in inventor's Patent No. 2,252,325 except for minor details of construction. Briefly, the unclamping connections include a link 136 connected at one end to the crank actuated pivot 114 and at its other end with an operating lever 138 rotatably mounted on a shaft 140 secured in the jack frame. Also rotatable on the shaft 140 and releasably connected to the operating lever 138 is a segmental unclamping and resetting lever 142 arranged at its upper end to receive slidingly a flexible cable 144 connected with the last pin slide 126. The cable 144 has at its resetting lever engaging end a fixed block 146 against which the resetting lever acts. The use of a flexible cable in place of a rigid link, such as is employed in the machine of the patent last referred to, enables the cradle and carriage to move freely with respect to the jack frame during lasting operations without resistance such as might be encountered in the patented construction. While the carriage is being tipped about the ball portion of a shoe during lasting operations, the cable slides through the resetting lever in the manner indicated in Fig. 2.

To connect the operating lever 138 releasably with the resetting lever 142, the lever 138 has pivoted thereon a latch lever 148 the hooked end of which is movable toward and from engagement with a pin 150 on the resetting lever. At the end of a lasting operation, the latch supporting and operating lever 138 is moved toward the resetting lever to engage the latch lever with the pin 150. For urging the latch lever against the pin, the latch lever is connected with a coil spring 152 stretched between the latch lever and a fastening on the operating lever 138. At the end of the lasting operation, the cam shaft 70 is reversed to bring the connected mechanisms to starting position and, during the reverse rotation, the latch lever 148 draws the resetting lever 142 with it and, through the cable 144, unclamps the

shoe and resets the last pin slide 126 in a position to receive a new shoe.

In the machine of inventor's said prior patents, the last pin on the shoe supporting means is slidingly and yieldingly mounted for vertical movement in the last pin slide. When a shoe is applied to the jack, downward pressure applied to the bottom of the shoe engaging the last pin causes the last pin slide to be released for movement toward the toe rest, the last pin being arranged when depressed to release the last pin slide for shoe clamping movement toward the toe rest. Due to the mounting of the cradle in the jack frame and the general arrangement of the jack in the patented machine, difficulty has been encountered in some cases in actuating the last pin to release the last pin slide for clamping a shoe in operating position and, in the present construction, with a movable carriage in addition to the cradle, further complication in the slide releasing connection would arise unless special provision were made for avoiding this difficulty.

To release the last pin slide 126 for shoe clamping movement toward the toe rest, in the present illustrated jack, the releasing operation is made entirely independent of the last pin 124, the last pin being rigidly secured in the last pin slide, and a tripping lever 154 is provided having a handle portion 156 located in line with the axis about which the cradle is mounted for rolling movement of the shoe in the jack frame. The tripping lever is fulcrumed on a pin 158 in the jack frame, and one arm of the lever engages an arm of an intermediate lever 160 also fulcrumed on the jack frame. The intermediate lever has an arm engaging the latch lever 148 so that, when the tripping lever is actuated toward the adjacent pivotal mounting 58 for the cradle (see Fig. 5), the latch lever will be disengaged from the pin on the resetting lever 142. As soon as the latch lever is disengaged from the pin on the resetting lever, the last pin slide moves toward the toe rest to clamp the shoe, the spring 130 shifting the slide until the movement is arrested by engagement of the toe of the shoe with the toe end gage 134. To hold the tripping lever in non-tripping position, the hubs of the tripping lever and the intermediate lever have coiled about them torsion springs 162 and 164, respectively, acting to press the lower end of the tripping lever against a pin 166 in the jack frame.

In straightening the toggle for lowering the jack at the end of the lasting operation in the patented machine, it is necessary to overcome the full force of the jack raising spring corresponding to the spring 32 in the present machine, this spring being constructed with sufficient mechanical strength to balance the weights of the jack and shoe and also to apply a force required to maintain proper upward pressure of the shoe against the presser feet 60 of the lasting units. The cam for actuating the toggle straightening and jack lowering lever 48 is of necessity cut with a sharp rise acting at the extreme end of the lasting operation on a shoe. As a result, the toggle is straightened more rapidly than the jack parts will drop, by reason of their weight, away from the lasting units. Due to the straightening of the toggle, the jack raising cord 36, therefore, is slackened and, as soon as the jack parts drop to the limit of the slackness in the cord, a severe shock will be imparted to the cord with consequent undesirable reactions in the toggle and the jack parts themselves. To avoid the results of reaction in the toggle after being straightened, in the machine of

inventor's Patent No. 2,247,443, a dashpot is provided arranged to resist movement of the toggle as it nears straightened position, thereby reducing the speed at which the toggle is straightened and absorbing the shock occasioned by reaction of the heavy jack parts when they reach the limit of their lowering movement.

As has been stated, a feature of the present invention consists in the use of weight counterbalancing means to enable the jack to descend for a short distance relatively slowly even though the toggle 38, 40 is straightened quickly, without subjecting the toggle to undesirable shock and jar. Instead of utilizing the spring 32 in the present illustrated machine to support and raise the jack as well as to force the shoe against the presser feet 60, a substantial proportion of the weight of the jack and shoe is taken up in the present machine by a jack weight counterbalancing spring 168 stretched between a bar 170 in the machine framework at the upper end of the spring and an arm 172 at its lower end pivotally mounted at 175 on an arm of the lever 34 (see Fig. 12). The force of the spring 168 is adjusted suitably to balance the weight of the jack and shoe substantially except for a few ounces of excess weight in the jack. The lowering movement of the jack, therefore, is effected by a slight excess of weight in the jack and supported shoe over the force applied by the counterbalancing spring 168. Being of a relatively heavy construction, the excess or uncounterbalanced portion of the weight of the jack over the force of the counterbalancing spring is only slightly greater than that necessary to overcome friction in the parts, thus causing the jack to settle gradually to the lower limit of its movement. Under these conditions, the speed at which the jack descends after the toggle is straightened is less than that of the lever 34 and a substantial amount of separation occurs between the lever and the arm 172, as illustrated in the broken-line position of Fig. 1. The downward movement of the arm 172 thereafter will not produce undesirable shock or reaction on the toggle, on the cord 36 or on the jack parts themselves when the jack reaches the lower limit of its movement because the settling movement is so gradual.

To regulate the lower limit of the jack movement, the arm 172 carries a set screw 174 acting as a stop against the lever 34. The arrangement between the arm 172 and the lever 34 comprises a loose joint in the jack raising and shoe pressing system of connections which prevents formation of slack in the jack raising cord 36, the counterbalancing spring 168 acting at all times to maintain tension in the cord so as to keep it under control and prevent its displacement from the various guides and pulleys over which it passes.

As a means for holding the two members of the toggle 38, 40 in alignment after the toggle has been straightened, the toggle connected arm of the lever 34 has fastened to it a spring 176 stretched between the arm and an eye on the machine framework. The purpose of the spring 176 is to insure application of a light pressure on the toggle after being straightened even though the force of the jack raising spring 32 is substantially relaxed.

Since the jack raising spring 32 no longer is required to support the entire weight of the jack and shoe, a relatively weaker spring may be employed in this position than in the patented machine and no change in its tension is required.

The mechanism for controlling the tension of the jack raising spring to increase during lasting operations and alternately to diminish the tension during that part of the cycle of operations in which the shoe is fed, therefore, is not subject to such severe strains and may be arranged more conveniently for adjustment purposes and accuracy of timing.

The means for increasing and diminishing the pressure of the shoe against the presser feet of the lasting units and the tension of the jack raising spring 32 during action of the staple driving devices in the lasting units in the present machine comprises a single lever 178 fulcrumed on a shaft 180 in the upper part of the machine framework and provided with a cam roll 182 engaging a cam 184 on the main operating cam shaft 4. The lever 178 is directly connected with the upper end of the spring 32 so that no lost motion occurs between the lever and the spring, and the increase of spring pressure is applied accurately in each lasting cycle at the time in which it is desired. Since the full weight of the jack is no longer supported by this mechanism, much simpler and lighter operating connections and parts may be employed than in the patented machine.

The nature and scope of the invention having been indicated and an embodiment of the several features of the invention having been specifically described, what is claimed is:

1. A machine for use in the manufacture of shoes having devices acting along the marginal portion of a shoe bottom to perform an operation progressively along the shoe, shoe supporting means, a cradle for the shoe supporting means, and a movable jack frame in which the cradle is pivotally mounted for rolling movement of the shoe in the supporting means about an axis extending lengthwise of the shoe, in combination with a carriage in which the shoe supporting means is secured mounted in the cradle for pitching movement of the shoe about an axis extending widthwise of the shoe in the supporting means.

2. A machine for use in the manufacture of shoes having devices acting along the marginal portion of a shoe bottom to perform an operation progressively along the shoe, shoe supporting means, a cradle for the shoe supporting means, and a movable jack frame in which the cradle is pivotally mounted for rolling movement of the shoe in the supporting means about an axis extending lengthwise of the shoe, in combination with a carriage in which the shoe supporting means is secured mounted in the cradle for pitching movement of the shoe about an axis extending widthwise of the shoe in the supporting means, and mechanism in the jack frame for actuating the carriage relatively to the cradle during operation of said devices.

3. A machine for use in the manufacture of shoes having devices acting along the marginal portion of a shoe bottom to perform an operation progressively along the shoe, shoe supporting means, a cradle for the shoe supporting means, and a movable jack frame in which the cradle is pivotally mounted for rolling movement of the shoe in the supporting means about an axis extending lengthwise of the shoe, in combination with a carriage in which the shoe supporting means is secured mounted in the cradle for pitching movement of the shoe about an axis extending widthwise of the shoe in the supporting means, a cam shaft in the jack frame, and mechanisms driven from the cam shaft for shift-

ing the cradle in the frame and for actuating the carriage relatively to the cradle during operation of said devices.

4. A machine for use in the manufacture of shoes having devices acting along the marginal portion of a shoe bottom to perform an operation progressively along the shoe, shoe supporting means, a cradle for the shoe supporting means, and a jack frame in which the cradle is pivotally mounted for rolling movement of the shoe in the supporting means about an axis extending lengthwise of the shoe, in combination with a carriage in which the shoe supporting means is secured mounted in the cradle for pitching movement of the shoe about an axis extending widthwise of the shoe in the supporting means, a cam shaft in the frame, mechanism including disconnectible connections driven from the cam shaft for actuating the carriage relatively to the cradle, and means for connecting said connections during operation of said devices and for disconnecting and locking said connections thereafter.

5. A machine for use in the manufacture of shoes having devices acting along the marginal portion of a shoe bottom to perform an operation progressively along the shoe, shoe supporting means, a cradle for the shoe supporting means, and a jack frame in which the cradle is pivotally mounted for rolling movement of the shoe in the supporting means about an axis extending lengthwise of the shoe, in combination with a carriage in which the shoe supporting means is secured mounted in the cradle for pitching movement of the shoe about an axis extending widthwise of the shoe in the supporting means, a cam shaft in the frame, mechanism including disconnectible connections driven from the cam shaft for actuating the carriage in the cradle, and a crank driven by the cam shaft for causing the disconnectible connections to be connected during one part of the cam shaft rotation and for causing said connections to be disconnected and the carriage locked during another part of the cam shaft rotation.

6. A machine for use in the manufacture of shoes having devices acting along the marginal portion of a shoe bottom to perform an operation progressively along the shoe, shoe supporting means, a carriage in which the shoe supporting means is secured, a jack frame in which the carriage is movably mounted, and a cam shaft in the frame, in combination with mechanism including a hooked link and a cooperating pin driven from the cam shaft for imparting movement to the carriage in the frame, a crank driven from the cam shaft for engaging or disengaging the hook and pin to render the mechanism operative or inoperative, a toggle for locking the mechanism from operation when the hooked link is disengaged from the pin, an arm on the cam shaft, and a latch on the arm, acting when the hooked link is being engaged with the pin to break the locking toggle.

7. A machine for use in the manufacture of shoes having devices acting along the marginal portion of a shoe bottom to perform an operation progressively along the shoe, shoe supporting means, a cradle for the shoe supporting means, and a jack frame in which the cradle is pivotally mounted for rolling movement of the shoe in the supporting means about an axis extending lengthwise of the shoe, a cam shaft in the frame, means for rotating the cam shaft in one direction during operation of the said devices

and for rotating the cam shaft in the opposite direction after the operation is completed, and a cam on the cam shaft for shifting the cradle relatively to the frame during operation of said devices, in combination with a carriage in which the shoe supporting means is secured mounted on the cradle, mechanism including disconnectible connections driven from the cam shaft for actuating the carriage in the cradle, and means for connecting the disconnectible connections during a substantial part of the operation of said devices and for disconnecting and locking said carriage connections thereafter.

8. A machine for use in the manufacture of shoes having devices acting along the marginal portion of a shoe bottom to perform an operation progressively along the shoe, a carriage, a jack frame in which the carriage is movably mounted, a cam shaft in the frame, clamping means mounted on the carriage comprising a toe rest, a heel support, a slide on which the heel support is mounted, a spring tending to move the slide toward the toe rest to clamp a shoe, and means in the jack frame for unclamping the shoe, in combination with a flexible cable stretched between the heel support slide and the unclamping means to render the unclamping means operative.

9. A machine for use in the manufacture of high arch shoes, having devices acting along the marginal portion of a shoe bottom to perform an operation progressively along the shoe, shoe supporting means, a jack frame for the supporting means, and means for imparting a feeding movement to the jack frame lengthwise of the shoe on the supporting means, in combination with a carriage on which the shoe supporting means is mounted guided in the frame for pitching movement about an axis extending widthwise of the shoe on the supporting means and intersecting the shoe close to the ball line of the shoe, and mechanism actuated in timed relation with the feeding means for imparting pitching movement to the carriage in opposite directions to enable operations to be performed along the shoe at either side of the ball line while presenting the bottom of the shoe at the point of operation substantially at right angles to the operating devices.

10. A machine for use in the manufacture of high arch shoes, having devices acting along the marginal portion of a shoe bottom to perform an operation progressively along the shoe, shoe supporting means, a jack frame for the supporting means, and means for imparting a feeding movement to the jack frame lengthwise of the shoe on the supporting means, in combination with a carriage on which the shoe supporting means is mounted, and means for guiding the carriage in the frame comprising rolls and an arcuate guideway centered about an axis extending widthwise of the shoe on the supporting means and intersecting the shoe substantially at the center of its lengthwise curvature at the ball line of the shoe.

11. A machine for use in the manufacture of shoes, having a jack frame, shoe supporting means in the jack frame, devices for operating upon a shoe including an abutment to engage the shoe, means for pressing a shoe on the supporting means yieldingly against the abutment, means for feeding the jack frame step by step to present the shoe progressively in different relations to the abutment, and a shaft for actuating the operating devices, in combination with a cam on said shaft for controlling the pressing

means to diminish the pressure of the shoe on the abutment while the shoe is being fed.

12. A machine for use in the manufacture of shoes, having a jack frame, shoe supporting means in the jack frame, devices for operating upon a shoe including an abutment to engage the shoe, means for pressing a shoe on the supporting means yieldingly against the abutment, means for feeding the jack frame step by step to present the shoe progressively in different relations to the abutment, a shaft for actuating the operating devices, and a pattern cam shaft for the feeding means driven intermittently from the operating shaft and arranged to rotate once during operation upon each shoe, in combination with a cam on the operating shaft for controlling the pressing means to diminish the pressure of the shoe on the abutment while the pattern cam shaft is being rotated to feed the shoe and to increase the pressure while the operating devices are being actuated.

13. A machine for use in the manufacture of shoes having devices acting along the marginal portion of a shoe bottom for performing an operation progressively along the shoe, a jack frame, a cradle in the frame, shoe supporting and releasable clamping means on the cradle, and mounting means for the cradle in the jack frame to enable the cradle to roll about an axis extending lengthwise of the shoe in the supporting means, in combination with a tripping lever for the shoe clamping means in the jack frame having a handle portion located in line with the axis about which the cradle rolls in the frame.

14. A machine for use in the manufacture of shoes having devices acting along the marginal portion of a shoe bottom for performing an operation progressively along the shoe, a jack frame, a cradle in the frame, shoe supporting and releasable clamping means on the cradle, mounting means for the cradle in the jack frame to enable the cradle to roll about an axis extending lengthwise of the shoe in the supporting means, and mechanism in the jack frame for actuating the shoe clamping means to unclamp the shoe, in combination with a tripping lever for the shoe clamping means in the jack frame for causing the shoe clamping mechanism to clamp the shoe.

15. A machine for use in the manufacture of shoes having devices acting along the marginal portion of a shoe bottom for performing an operation progressively along the shoe, a jack frame, a cradle in the frame, shoe supporting and releasable clamping means on the cradle, and mounting means for the cradle in the jack frame to enable the cradle to roll about an axis extending lengthwise of the shoe in the supporting means, in combination with mechanism in the frame for actuating the shoe clamping means comprising a resetting lever mounted in the frame, power driven means for moving the resetting lever, a latch for holding the resetting lever releasably in shoe unclamping position, and a flexible cable connecting the resetting lever with the clamping means.

16. A machine for use in the manufacture of shoes having devices acting along the marginal portion of a shoe bottom for performing an operation progressively along the shoe, a jack frame, a cradle in the frame, shoe supporting and releasable clamping means on the cradle, and mounting means for the cradle in the jack frame to enable the cradle to roll about an axis extending lengthwise of the shoe in the supporting

means, in combination with mechanism in the frame for actuating the shoe clamping means comprising a resetting lever mounted in the frame, a connection between the clamping means and the resetting lever, a latch for releasably holding the resetting lever in clamp resetting position, a supporting lever on which the latch is pivotally mounted, a power driven member for moving the supporting lever to engage the latch with the resetting lever and to move the 10 resetting lever to reset the clamping means, and a handle in the jack frame for releasing the resetting lever from the latch to clamp a shoe.

17. A machine for use in the manufacture of shoes, having devices acting along the marginal portion of a shoe bottom to perform an operation progressively along the shoe, a jack frame, shoe supporting means on the frame, comprising a last pin and a toe rest, a slide on which the last pin is mounted, a guideway inclined to the length of the last pin in the shoe supporting means to permit shoe clamping movement of the slide toward the toe rest, a spring for moving the slide toward the toe rest, and means for holding the slide releasably away from the toe rest before jacking a shoe, in combination with a toe gage having a toe end engaging surface disposed at right angles to the guideway for the last pin slide to avoid a component of force from the spring tending to force the toe of the shoe upwardly away from the toe rest.

18. A machine for use in the manufacture of shoes, having devices acting along the marginal portion of a shoe bottom to perform an operation progressively along the shoe, an operating cam shaft, connections for actuating said devices from the cam shaft, a shoe supporting jack, means including a spring exerting upward pressure on the jack to press the shoe toward said devices, a toggle connected and arranged to be flexed during movements of the jack, and a pattern cam acting at the completion of the operation to straighten the toggle and thereby render the spring inoperative to press the shoe against said devices, in combination with means separate from the spring for counterbalancing a substantial portion of the weight of the jack, and a loose joint in the shoe pressing means to enable the toggle to be straightened quickly without subjecting the toggle to reaction due to the full force of the jack weight, the shoe thereon moving relatively slowly away from operating position against said devices under the force of the remaining uncounterbalanced portion of the jack weight.

19. A machine for use in the manufacture of shoes, having devices acting along the marginal portion of a shoe bottom to perform an operation progressively along the shoe, an operating cam shaft, connections for actuating said devices from the cam shaft, a shoe supporting jack, means including a spring exerting upward pressure on the jack to press the shoe toward said devices, a toggle connected and arranged to be flexed during movements of the jack, and a pattern cam acting at the completion of the operation to straighten the toggle and thereby render the spring inoperative to press the shoe against said devices, in combination with means separate from the spring for counterbalancing a substantial portion of the weight of the jack, a loose joint in the shoe pressing means to enable the toggle to be straightened quickly without subjecting the toggle to reaction due to the full force of the jack weight, the shoe thereon mov-

ing relatively slowly away from operating position against said devices under the force of the remaining uncounterbalanced portion of the jack weight, and a spring in the pressing means acting between the toggle and the loose joint to hold the toggle in straightened position when temporarily freed from the weight of the jack.

20. A machine for use in the manufacture of shoes, having devices acting along the marginal portion of a shoe bottom to perform an operation progressively along the shoe, an operating cam shaft, connections for actuating said devices from the cam shaft, a shoe supporting jack, a cable connected to the jack for transmitting force to press the shoe toward the operation performing devices, a lever connected to the cable, yielding means acting on the lever to counterbalance a substantial portion of the weight of the jack, an arm acting against the lever to move the lever in a direction for lowering the jack away from operating position, a toggle connected to the arm for holding the jack in lowered position and arranged to be flexed during movements of the jack in its upper position, and a pattern cam acting at the completion of the operation to straighten the toggle, in combination with a spring connected to the lever to exert upward pressure on the jack which, added to the force of the counterbalancing means, holds the shoe on the jack forcibly against the operation performing devices.

21. A machine for use in the manufacture of shoes, having devices acting along the marginal portion of a shoe bottom to perform an operation progressively along the shoe, an operating cam shaft, a shoe supporting jack, a toggle connected to the jack and arranged to be flexed during movements of the jack, and a pattern cam acting at the completion of the operation on a shoe to straighten the toggle, in combination with a jack lifting lever, a spring connected to the jack lifting lever for exerting upward force on the jack to press the shoe against the operation performing devices, an arm arranged for limited movement toward and from the lever, a cable connected to the arm, yielding means acting on the arm separately from the pressure exerting spring for counterbalancing a substantial portion of the weight of the jack, and a second arm having a connection with one end of the toggle and acting against the lifting lever to slacken the cable.

22. A machine for use in the manufacture of shoes, having a jack frame, shoe-supporting means in the jack frame, devices for operating upon a shoe including an abutment to engage the shoe, and means for feeding the jack frame step by step to present the shoe progressively in different relations to the abutment, in combination with means for pressing the shoe on the supporting means against the abutment comprising two yielding members, one of which substantially balances the weight of the jack and shoe and the other of which is actuated alternately to force the shoe against the abutment and to diminish the pressure on the abutment during feed of the shoe.

23. A machine for use in the manufacture of shoes, having a jack frame, shoe-supporting means in the jack frame, devices for operating upon a shoe including an abutment to engage the shoe, and means for feeding the jack frame step by step to present the shoe progressively in different relations to the abutment, in combination with means for pressing the shoe on the

supporting means against the abutment comprising two separate yielding members, one of which substantially balances the weight of the jack and shoe and the other of which forces the shoe against the abutment, and mechanism for increasing during operation of said devices the tension of the member which forces the shoe against the abutment and alternately for diminishing the tension of said member during feed of the shoe while the tension on the other member remains unchanged.
